UNITED STATES PATENT OFFICE.

RUDOLPH CLEAVELAND, OF COVINGTON, PENNSYLVANIA.

IMPROVEMENT IN THE MODES OF CONNECTING PITMEN WITH SHAFTS.

Specification forming part of Letters Patent No. **142,616**, dated September 9, 1873; application filed April 19, 1873.

To all whom it may concern:

Be it known that I, RUDOLPH CLEAVELAND, of Covington, in the county of Tioga and State of Pennsylvania, have invented a new and useful Improvement in Devices for Operating the Dashers of Churns, or for other analogous purposes; and I do hereby declare that the following is a full, clear, and exact description of the same, reference being had to the accompanying drawing forming a part of this specification.

I will illustrate my invention by describing it in connection with a churn.

Figure 1 is a detail vertical section of a churn taken through the line *x x* of Fig. 2. Fig. 2 is a top view of the same. Fig. 3 is a detail view of a bar for connecting the churn-shaft with the shaft of a driving power.

The invention consists in the mode of relatively constructing a bar and hand-crank shaft, so that other power than that of the hand may be employed to operate, in the manner herein-after described.

A B represent a churn-body having a socket or pivot, C, to receive the lower end of a dasher-shaft, D E, and a cover, F, made in two unequal parts hinged to each other. To the upper end of the shaft D is detachably attached a bevel-gear wheel, G, the teeth of which mesh into the teeth of the bevel-gear wheel H attached to the horizontal shaft I. One journal

of the shaft I revolves in a hole in the upper end of a bar, J, attached to the churn-body A, and its other journal revolves in a notch in the upper end of a similar bar, K, attached to the opposite side of said churn-body, where it is held in place by a spring-catch, L, also attached to said churn-body. One end of the shaft I projects, is flattened, and has a longitudinal slot formed in it, as shown in Figs. 1 and 2. M is a crank, in which is formed a slot to receive the flattened end of the shaft I, so that the churn may be operated by hand-power when desired. N is a bar, in one end of which is formed a slot to receive the flattened end of the shaft I, when it is secured in place by a spring catch-pin, O, as shown in Fig. 3. The other end of the bar N is slotted to receive the end of the shaft of the driving power, where it is secured in place by a bolt and nut, P.

Having thus described my invention, what I claim as new, and desire to secure by Letters Patent, is—

The bar N slotted at both ends, in combination with spring catch-pin O and end-slotted end-flattened shaft I, to enable power to be applied to the latter, as described.

RUDOLPH CLEAVELAND.
